AUXILIARY CHARGING DEVICE FOR
INTERNAL-COMBUSTION ENGINESMerritt A. Zimmerman, Cleveland, Ohio, assignor
to Associated Laboratories, Inc., Cleveland,
Ohio, a corporation of Ohio

Application September 9, 1946, Serial No. 695,584

4 Claims. (Cl. 261—18)

1

This invention is in the nature of an improvement on and continuation in part of my "Supplementary fuel injector," Serial No. 611,632, filed August 20, 1945, now abandoned.

The inventions of both my prior application and the present application relate to a novel construction of means to deliver an additional amount of fuel or liquid into the combustible mixture of an internal combustion engine during the action of opening the throttle.

In the present case, as in the former, the general object is to provide a simple effective device which will supply supplementary fluid for increasing the effectiveness of combustion and for diminishing detonation effects, and which functions instantly and with certainty.

Among the objects of the present invention is the provision of a supplementary liquid container and charge forming and delivering injector which may be installed with standard carburetors with a minimum of expense and all parts of which may be those easily obtainable and so specifically designed in my novel arrangement as to provide for greatest convenience and simplicity of installation upon present standard automobiles.

As stated in my prior application, it had been proven that the most effective and desirable time to inject an anti-detonant or supplementary liquid is before the detonation sets in or begins. Experience has proven that about one half as much liquid, such as water, will prevent the detonating condition if injected in anticipation of the conditions causing it, as would be required to suppress detonation after it starts.

The present invention includes the provision of the means for carrying out the foregoing objects and others stated in my prior application, and more specifically the following; namely, producing a blanketing effect to suppress detonation on subsequent peak pressures or temperatures after a starting or accelerating impulse; forcibly injecting the supplementary liquid without interfering with normal throttle control; effecting the formation of a charge consequent upon each return or partial closing throttle movement; providing for briefly continuing the pressure delivery of the supplementary liquid after each throttle opening movement; which pressure delivery, however, shall instantly cease at any time that the throttle starts to close; the prevention of flooding by excess injection, and the attainment of all these with a minimum of simple durable parts comprising an accessory assemblage.

In the drawings I have shown a preferred 55

commercial form of my invention which has been proven satisfactory in accomplishing the foregoing and other objects which will become apparent in the following description relating thereto.

2

In the drawings,

Fig. 1 is an assembly view partly in section showing the supply vessel connections with the throttle and the mounting and the connecting 10 of the charge forming means with a standard carburetor;

Fig. 2 is a plan on an enlarged scale view of the injector cylinder and connections;

Fig. 3 is an enlarged axial section through the 15 valves and a portion of the injector cylinder, on the same scale as Fig. 2;

Fig. 4 is an enlarged sectional detail of the injector nozzle;

Fig. 5 is an elevation taken substantially on a 20 plane indicated by the line 5—5 of Fig. 3.

The auxiliary liquid container may be of any form and appropriate size, but I have found that a glass bottle or jug of a type widely used and easily available in most any locality, preferably 25 having about a gallon capacity, eliminates many objections and has advantages in this auxiliary and accessory assemblage.

Such a jar container is designated 10 in Fig. 1 and is preferably securely fastened under the 30 hood to the front wall of a driving compartment of an automobile by conveniently installed means, such, for example, as an L-shaped bracket plate 12 having rest portion 13 extending a suitable distance under the bottom of the jar 10, and 35 secured to the wall plate which is usually of metal and indicated at 15 by bolts 16.

Attached to the bracket 11 and extending around two sides of the bottle and meeting at the front are straps 18 having their ends 40 cured as by a screw bolt 19 to firmly clamp the container 10 securing it against vibration.

Extending into the jar 10 is a tube 20 firmly held in a cork or stopper 22 having a vent opening 23. The tube 20 preferably reaches substantially to the bottom of the inside of the supplementary liquid container and is connected at its upper end to a flexible tube or hose 25 leading to a nipple 26 communicating with an intake valve 28 formed on a head member 30 45 of the charge forming cylinder 35. This cylinder is provided with a piston 36 having a piston rod or stem 38 projecting outwardly from the cylinder 35 at the end opposite the valves and by which fluid is ejected through the discharge valve 40 from which extends a hose re-

ceiving nipple 42 from which liquid is led through the hose 44 to the injection jet nozzle extending into the carburetor C.

The cylinder 35 may be mounted in any convenient position, but for practical purposes I have found it convenient and desirable to provide an L-shaped bracket 68 which may be secured by bolts 64 to the front wall of the driving compartment, designated 15a which may be the same wall member as designated 15.

Another L-shaped bracket member 64 having upwardly extending portion 66 may be bolted as at 66, Figs. 2 and 5, to the valve head and cylinder 35 and longitudinal slots 62 formed in one or both of the members 60 and 64 receiving bolts 68 may provide for adjustably positioning the cylinder and associated parts 35.

The piston 36 is preferably connected to be actuated by the throttle rod, as follows:

A yoke member preferably formed of wire rod is shown as guided in an enlargement 37 on the cylinder to which the valve head 30 is secured, the yoke member slidably passing through openings formed in the members 36 and 37 and having a flattened enlargement provided with a hole 52 slideable on the valve stem 38 and a spring 70 surrounding the stem 38 is interposed between the flattened portion 68 of the yoke member 68 extending through a guide opening in a boss 72 formed at the rear of the cylinder.

The forward ends of the legs of the yoke 68 are shown as connected by bridge clamp members 75 having portions bent to embrace the ends of the clamp, as indicated at 76, and held in suitably adjusted position by screws 77. The members 75 have a central opening 78 through which extends a hook of a small link rod 88 having its other end secured to a screw held clamp bracket 82, suitably positioned on a throttle rod 85, which is connected in the usual manner to the rock arm 87 for turning the main throttle shaft 88 when the rock levers 90 and 91 are actuated by the foot throttle indicated at 95.

The outer end of the piston rod 38 may be provided with a suitable stop, here shown as a 45 cotter pin 39, by which the piston is retracted for charging as the throttle lever 85 and link 88 move to the right in Fig. 1.

As the throttle is opened, the throttle lever 87, link 85 and foot throttle member 95 move to the 50 left pulling on the link 88, the yoke 68 compresses the spring 70 to move the piston 36 to the left, discharging liquid from the cylinder through the valve 40 to the injector nozzle 50 and into the carburetor C, delivering an amount 55 corresponding to the extent of compression of the spring. Only a portion of the carburetor is shown, but it is indicated as a standard construction now used in many automobiles, having a butterfly choke 98, a main Venturi passage V 60 and an auxiliary venturi V^2 above the butterfly throttle valve, not shown.

The valves 28 and 30 may be any suitable durable check valves responsive to low pressure. As shown, they are self-contained in cages, indicated at 101, each having an enlarged portion which may be clamped between enlarged heads 102 of the nipple members 26 and 42, and having closure springs indicated at 104 acting against closure disks 105 (Fig. 3).

The valve 28 is positioned to permit flow into the cylinder and to act as a check against return flow therethrough, while its companion, the valve 30, is positioned to permit flow from the cylinder and to act as a check against suction 75

backwardly through the tube 44, assuring a pumping action drawing liquid from the container 10 and expelling it toward the carburetor.

The piston is preferably of the O-ring type 5 which has been found to effectively prevent leakage and to work very easily when lubricated by the water or auxiliary liquids.

It will be noted that friction on the piston rod is reduced to a minimum because it has no 10 packing glands, and it is additionally guided to position the O-ring by the connection of the piston rod with the yoke while the spring may pass freely through the opening in the extension 72.

15 The injection nozzle while being capable of manufacture with simple screw machine operations is somewhat critical in its arrangement to attain the most effective injection. In the preferred form, shown particularly in Fig. 4, it comprises a tubular element 51 having a threaded connection with the wall C of the carburetor, and which may be secured as by a small lock nut 52, and projects into the carburetor to a point near the center and over the auxiliary venturi 25 V^2 when used. Its passage 53 is shown as larger than the control jet opening 54 formed in a head member 55 fitted by threads into an enlarged opening in the outer end of the member 51, and having its outer wall of a size to permit 30 the hose connection 46 to pass over it and onto a portion of the member 51.

This jet opening is preferably about twenty-five to thirty-five thousandths of an inch in diameter, while the passage 53 leading therefrom 35 is somewhat larger, say, about one-sixteenth of an inch.

40 The fine jet emitted from the opening 54 passes forcibly through a larger passage 53, and I have found the efficiency is improved by providing an intake vent opening at 56 leading to the passage 53 at the carburetor side of the small jet.

To prevent clogging of the small jet I may 45 insert a plug of filter material into the tube, as indicated at 57.

In the position shown in Fig. 1 the foot throttle member 95 is at rest, and the throttle valve on the shaft 88 would be in closed or idling position.

For starting or accelerating the throttle rod and associated parts would be moved to the left, pulling on the link 88 and yoke 68 to advance the yoke along the stem or piston rod 38 compressing the spring 70 against a charge of liquid previously drawn into the cylinder 35. The spring 70 now exerts pressure closing the check valve 28 and opening the valve 30, forcing the passage of fluid through the tube 44 and through the jet opening 54 and passage 53 to the carburetor. This action is quick and actually simultaneously starts anti-detonant into the intake of the carburetor at the moment the main fuel passage is being opened, liquid from the jet 50 is atomized and enters the cylinders of the engine mixed with the operational fuel.

Varying distances of throttle opening cause 65 corresponding variation in compression of the spring 70 whereby fluid is caused to flow at rates corresponding to the power or torque requirements.

70 It will be seen that a slight movement of throttle opening will stress the spring 70 only sufficiently to exert a portion of its pressure against the piston 36. The result will be, as the spring 75 expands a part only of its length, to force only a

part of the liquid in the cylinder 35 into the tube 44, which normally is already filled. This results in a correspondingly short interval of discharge from the injection nozzle. If, however, the throttle is open to its fullest extent, this spring 70 will be compressed sufficiently to move the piston for a full stroke, providing this open position is maintained for a sufficient length of time to empty the cylinder.

Likewise, it will be noted that at the moment of such full opening movement the pressure on the spring 70 is at its maximum. Thus, injection is effected from the nozzle 50 into the carburetor at its highest pressure at the moment of greatest need. This assures the charge of auxiliary liquid entering the engine ahead of the high torque and other extreme conditions.

As stated, it is desirable to avoid gravity flow from the storage container 10, and although the valves 28 and 30 normally preclude this, the storage container is preferably mounted below the carburetor. During running conditions the passages to and from the cylinder remain filled with liquid so that the slightest operation of the yoke 68 and compression of the spring 70 produces the desired effect instantly.

It has been found that a one gallon jar filled with water will last through driving conditions of as high as 800 miles, although obviously the use of the auxiliary liquid would be faster under severe conditions.

From the foregoing description it will be seen that I have provided an auxiliary liquid injector device which may be installed quickly, and which comprises rugged simple parts not likely to get out of order, and by which the advantages enumerated above and those set forth at length in my prior application may be attained.

The auxiliary liquid may be plain water. However, various auxiliary fuels may be used if desired. A mixture suitable for use as a detonation preventive, as well as for increased fuel efficiency, is a mixture of approximately 50% water and 50% alcohol. Whatever the fluid the injection is positive and certain and does not continue after the engine is stopped and the ignition turned off, nor does it inject fuel when the automobile is coasting to a stop.

Various modifications may be made in the details of the construction described without departing from the spirit and intent of the invention as summarized in the appended claims.

Having thus described my invention, what I claim is:

1. An auxiliary fluid injector for an internal combustion engine comprising a container for liquid, an injector nozzle extending into the carburetor, a reciprocating pump and connections between the container and pump and between the

5 pump and nozzle, means rigidly mounting the pump with relation to the carburetor, the pump having an actuating rod extending outside the pump and movable axially toward and away from the carburetor, a yoke member having slide members parallel to said actuating rod and having a 10 slideable connection therewith, a spring between the yoke member and rod, and means connecting the yoke member with the carburetor throttle actuating means.

2. In a device of the character described in claim 1, in which said yoke has a removable link connection with the usual throttle rod.

3. An auxiliary fluid injector for an internal combustion engine, comprising a container for liquid, an injector nozzle extending into the carburetor, a reciprocating pump and tubular connections between the container and pump and between the pump and nozzle, means rigidly mounting the pump with relation to the carburetor, the pump having an actuating rod extending outside the pump and movable axially toward and away from the carburetor, a yoke member bridging across said actuating rod and movable with relation thereto and connected therewith for reciprocating the rod, a link attached to said yoke member and adapted to be connected to the usual throttle rod for the carburetor, a spring for moving the pump rod in one direction to inject fluid when the throttle rod yoke and link are moved, means for returning the pump rod in counter movement, and clamping means adjustable along the throttle rod and to which said link is connected whereby movement 20 of the carburetor throttle actuates the pump to force liquid under spring pressure into the injector nozzle.

4. The device of the character described in claim 3 in which said injector nozzle is provided with a vent opening to prevent carburetor suction drawing liquid through the nozzle.

MERRITT A. ZIMMERMAN.
